3-(2-HYDROXYETHYL)-4-METHYL-5-PHENYLOXA-ZOLIDINE AND CERTAIN ESTERS

Max J. Kalm, Skokie, and Kurt J. Rorig, Glenview, Ill., assignors to G. D. Searle & Co., Chicago, Ill., a corporation of Delaware

No Drawing. Filed July 29, 1959, Ser. No. 830,208

Claims priority, application Canada July 31, 1958

4 Claims. (Cl. 260—307)

This invention relates to 3-(2-hydroxyethyl)-4-methyl-5-phenyloxazolidine, its esters, and processes for the manufacture thereof. More particularly, this invention relates to compounds of the formula

wherein R represents hydrogen or an alkanoyl radical.

Among the alkanoyl radicals represented by R, especially lower alkanoyl radicals are preferred, which is to say radicals of the formula

wherein the lower alkyl constituent is such as methyl, ethyl, propyl, isopropyl, butyl, isobutyl, sec-butyl, tert-butyl, pentyl, isopentyl, tert-pentyl, neo-pentyl, hexyl, isohexyl, heptyl, octyl, and like C_nH_{2n+1} groupings embracive of fewer than 9 carbon atoms.

The compounds of this invention are variously useful, the free alcohol, 3-(2-hydroxyethyl)-4-methyl-5-phenyloxazolidine, being valuable as an intermediate both to the corresponding esters hereof and to certain morpholine derivatives described and claimed in our copending United States patent application, Serial No. 726,638, filed April 7, 1958, and which is a continuation of our application, Serial No. 659,224, filed May 15, 1957, now abandoned. The morpholine derivatives referred to are anorectic agents capable of substantial and sustained inhibition of the appetite; and, moreover, they are diuretics.

Both the alcohol and esters of this invention are characterized by highly desirable anti-bacterial and anti-fungal activities—representatively, against *B. subtilis* and *Trichophyton mentagrophytes*, respectively.

Equivalent to the basic oxazolidines of this invention for the purposes here described are their acid addition salts, of the formula

wherein R has the meaning hereinbefore assigned and X is one equivalent of an anion—for example, chloride, bromide, iodide, nitrate, phosphate, sulfate, sulfamate, methyl sulfate, ethyl sulfate, benzenesulfonate, toluenesulfonate, acetate, lactate, succinate, malate, maleate, tartrate, citrate, gluconate, ascorbate, benzoate, cinnamate, or the like—which, in combination with the anionic portion of a salt aforesaid, is neither pharmacologically nor otherwise undesirable in physiological dosage.

Manufacture of 3-(2-hydroxyethyl)-4-methyl-5-phenyl-

5

oxazolidine proceeds, unexpectedly, by mixing 2-(2-hydroxyethylamino)-1-phenyl-1-propanol

2

10

with aqueous formaldehyde. The corresponding esters derive by heating 3-(2-hydroxyethyl)-4-methyl-5-phenyloxazolidine with pyridine and an appropriate alkanic acid anhydride. The acid addition salts of the basic oxazolidines of this invention are obtained by simple admixture of the amine base with one equivalent of any of various inorganic and strong organic acids, the anionic portion of which conforms to X as hereinabove defined.

Conversion of 3-(2-hydroxyethyl)-4-methyl-5-phenyloxazolidine to the valuable morpholine derivatives of our Serial Nos. 726,638 and 659,224 is effected by serial treatment with a strong acid and a selected imide

20

ZH

the compounds so produced having the formula

25

35

wherein Z represents, optimally, a succinimido or phthalimido radical. A typical strong acid useful in this procedure is concentrated sulfuric acid, which is employed at temperatures sufficiently low (of the order of 35° C.) to avoid charring or other deleterious effect on the reaction constituents. It is postulated that the result of this acid treatment is 4-hydroxymethyl-3-methyl-2-phenylmorpholine

40

45

but however that may be, the material which results, upon heating with the selected imide in a lower alkanol (especially ethanol) solution, is converted to the corresponding imidomethyl morpholine.

The following examples describe in detail compounds illustrative of the present invention and methods which have been devised for their manufacture. However, the invention is not to be construed as limited thereby, either in spirit or in scope, since it will be apparent to those skilled in the art of organic synthesis that many modifications, both of materials and of methods, may be practiced without departing from the purpose and intent of this disclosure. Throughout the examples hereinafter set forth, temperatures are given in degrees centigrade and relative amounts of materials in parts by weight, except as otherwise noted.

Example 1

70 A. 3-(2-hydroxyethyl)-4-methyl-5-phenyloxazolidine.—A suspension of 156 parts of 2-(2-hydroxyethylamino)-1-phenyl-1-propanol in 400 parts of water is

3

thoroughly mixed with 70 parts of 36% formalin. Solid matter disappears and a heavy oil is formed in process. The resultant mixture is extracted with chloroform, and the chloroform extract is dried over anhydrous sodium sulfate and stripped of solvent by distillation. The residual yellow oil is 3-(2-hydroxyethyl)-4-methyl-5-phenyloxazolidine, of the formula

10

4

line, melting at 127-130°. The product has the formula

15

B. 3-(2-hydroxyethyl)-4-methyl-5-phenyloxazolidine hydrochloride.—A solution of 3-(2-hydroxyethyl)-4-methyl-5-phenyloxazolidine in absolute ethanol, made acid with a slight excess of 2-propanolic hydrogen chloride and subsequently diluted with anhydrous ether, affords 3-(2-hydroxyethyl)-4-methyl-5-phenyloxazolidine hydrochloride as a colorless, hygroscopic, crystalline precipitate which, recovered on a filter and dried in vacuo, melts at 107-110°.

Example 2

3-methyl-2-phenyl-4-phthalimidomethylmorpholine.—To 360 parts of concentrated sulfuric acid at less than 35° is added, portionwise with agitation during 3 hours, the 3-(2-hydroxyethyl)-4-methyl-5-phenyloxazolidine obtained by the procedure of Example 1A. Following the addition, agitation is continued for one hour, whereupon the mixture is let stand for 15 hours at room temperatures and then neutralized with aqueous caustic in the presence of sufficient ice (representatively, 200 parts) to insure that the temperature does not rise above 35°. The resultant mixture is extracted with benzene, and the benzene extract is dried over anhydrous potassium carbonate and then stripped of solvent by distillation.

To 21 parts of the yellow oil obtained as the residue, dissolved in 40 parts of ethanol, is added, with agitation, 10 parts of phthalimide. Solution occurs. The solution is heated at the boiling point under reflux for 30 minutes, then filtered hot. From the filtrate, on cooling, 3-methyl-2-phenyl-4-phthalimidomethylmorpholine precipitates. The product is collected on a filter and recrystallized from 2-propanol. The 3-methyl-2-phenyl-4-phthalimidomethylmorpholine thus obtained melts at 142-144° and has the formula

Example 3

3-methyl-2-phenyl-4-succinimidomethylmorpholine.—Substitution of approximately 7 parts of succinimide for the 10 parts of phthalimide called for in Example 2 affords 3-methyl-2-phenyl-4-succinimidomethylmorpho-

line, melting at 127-130°. The product has the formula

B. 3-(2-acetoxyethyl)-4-methyl-5-phenyloxazolidine hydrochloride.—A solution of 3-(2-acetoxyethyl)-4-methyl-5-phenyloxazolidine in absolute ethanol, made acid with a slight excess of 2-propanolic hydrogen chloride and subsequently diluted with anhydrous ether, affords 3-(2-acetoxyethyl)-4-methyl-5-phenyloxazolidine hydrochloride as a colorless, crystalline precipitate which, recovered on a filter and dried in vacuo, is further purified by recrystallization from a mixture of absolute ethanol and anhydrous ether. The product is obtained in the form of needles, M.P. 134-138° (with decomposition).

What is claimed is:

1. A compound of the formula

45 wherein R is selected from the group consisting of hydrogen and lower alkanoyl radicals.

2. 3-(2-hydroxyethyl)-4-methyl-5-phenyloxazolidine.

3. A compound of the formula

4. 3-(2-acetoxyethyl)-4-methyl-5-phenyloxazolidine.
